United States Patent Office

Des. 192,781
Patented May 8, 1962

192,781

SCARF

Gordon O. Palmer, Cliffside Park, N.J., assignor to Max Mandel Laces, Inc., New York, N.Y., a corporation of New York

Filed Jan. 11, 1962, Ser. No. 68,267

Term of patent 3½ years

(Cl. D92—26)

The FIGURE is a plan view of a scarf showing my new design.

The scarf is shown over a dark background to bring out the details of the design.

I claim:

The ornamental design for a scarf, substantially as shown and described.
